3 Claims

ABSTRACT OF THE DISCLOSURE

Perhydro 1,4,9,9-tetramethyl-4,7-methanoazulenones useful as olfactory agents; and perfume compositions containing such azulenones.

This application is a division of application Ser. No. 735,544, filed on June 10, 1968, now U.S. Pat. 3,679,749.

BACKGROUND OF THE INVENTION

Materials which can provide amber and woody fragrance notes are known in the art of perfumery. Many of the natural materials which provide such fragrances and contribute desired nuances to perfume compositions are high in cost, variable in quality from one batch or crop to another, and/or are generally subject to the vagaries of natural products.

There is accordingly a continuing effort to find synthetic materials which will replace the essential fragrance notes of perfume compositions, but many of these synthetic materials either have the desired nuance only to a relatively small degree or else contribute undesirable or unwanted odors to compositions. Buchi et al., 83 J.A.C.S. 927 (1961), shows the production of a material called "patchouline" which is stated to be octahydro-1,4,9,9-tetramethyl-3a,7-methanoazulen-5(4H)-one.

THE INVENTION

This invention comprises the novel compositions and component mixtures comprised in such compositions, as well as the novel processes and steps of processes according to which such compositions may be manufactured, specific embodiments of which are described hereinafter by way of example only and in accordance with what is now considered the preferred manner of practicing the invention.

Briefly, the present invention relates to certain perhydro-1,4,9,9-tetramethyl-4,7-methanoazulenones and processes for their production. These materials are ketones having the formula

wherein one of R₁, R₂ and R₃ is oxygen and each of the other two represents two hydrogen atoms. It also relates to the use of these ketones as olfactory agents and in perfume compositions. The novel azulenones of the present invention provide a superior amber, precious wood, camphoraceous fragrance note and are much more intense than those previously known. Accordingly, smaller quantities can be used to impart a woody amber fragrance to perfume compositions and to perfumed articles, such as soap, face powder and other articles as disclosed hereinafter.

2

The novel materials according to the present invention can be considered as perhydro derivatives of methanoazulene and are octahydro-1,4,9,9-tetramethyl-4,7-methanoazulen-3(2H)-one, I; octahydro-1,4,9,9-tetramethyl-4,7-methanoazulen-2(3H)-one, II; octahydro-1,4,9,9-tetramethyl-4,7-methanoazulen-8(7H)-one, III; and mixtures thereof.

15 It will be appreciated that the foregoing structures include the various stereoisomeric forms.

I and II can be used individually or in admixture with each other or with III. Generally, III is utilized in admixture with the other two novel materials, and in many aspects of the present invention a mixture of the three ketones is preferred.

20 The ketones of this invention are useful as olfactory agents and fragrances. They have a camphoraceous woody amber fragrance in their own right and can impart this fragrance note to perfume compositions and perfumed articles according to the present invention. They can either be formulated into, or used as components of, perfume compositions.

25 The term "perfume composition" is used herein to mean a mixture of organic compounds, including, for example, alcohols, aldehydes, ketones, esters and frequently hydrocarbons which are admixed so that the combined odors of the individual components produce a pleasant or desired fragrance. Such perfume compositions usually contain: (a) the main note or the "bouquet" or foundation-stone of the composition; (b) modifiers which round-off and accompany the main note; (c) fixatives which include odorous substances which lend a particular note to the perfume throughout all stages of evaporation, and substances which retard evaporation; and (d) top-notes which are usually low-boiling fresh-smelling materials.

30 In perfume compositions the individual component will contribute its particular olfactory characteristics, but the overall effect of the perfume composition will be the sum of the effect of each ingredient. Thus, the individual compounds of this invention, or mixtures thereof, can be used to alter the aroma characteristics of a perfume composition, for example, by highlighting or moderating the olfactory reaction contributed by another ingredient in the composition.

35 The amount of mixtures or compounds of this invention which will be effective in perfume compositions depends on many factors, including the other ingredients, their amounts and the effects which are desired. It has been found that perfume compositions containing as little as 2% by weight of mixtures or compounds of this invention, or even less, may be used to impart a fine woody amber odor to soaps, cosmetics and other products. The 40 amount employed can range up to 7% or higher and will depend on considerations of cost, nature of the end product, the effect desired on the finished product and the particular fragrance sought.

45 The azulene ketones described herein can be used alone or in a perfume composition as olfactory components in detergents and soaps; space deodorants; perfumes; colognes; bath preparations such as bath oil, bath salts; hair preparations such as lacquers; brilliantines, pomades, and shampoos; cosmetic preparations such as creams, deodorants, hand lotions, sun screens; powders such as talc, dusting powders, face powder; and the like. When used as an olfactory component of a perfumed article, as little as

0.011% of the novel ketone will suffice to impart an amber, camphoraceous woody odor.

In addition, the perfume composition can contain a vehicle or carrier for other ingredients. The vehicle can be a liquid such as alcohol, glycol, or the like. The carrier can be an absorbent or adsorbent solid such as a gum or components for encapsulating the composition.

The examples which appear hereinbelow illustrate perfume mixtures, soap and other formulations within the scope of this invention. It is to be understood that these compositions are preferred examples, and the invention is not to be considered as restricted thereto except as indicated in the appended claims.

The ketones of this invention can be prepared by a novel process which comprises treating a saturated alcohol having the structure

or mixtures of such alcohols wherein one of R₄, R₅ and R₆ is OH and the other two are H with an agent which will oxidize a secondary hydroxyl to a carbonyl and provide the novel ketones having the structure

wherein R₁, R₂, and R₃ are as disclosed above.

More specifically, the perhydro alcohol or alcohols are oxidized to a ketone by a strong oxidizing agent such as chromium trioxide, an alkali-metal dichromate such as potassium dichromate, sodium dichromate and the like, or an alkali-metal permanganate such as potassium permanganate and the like. It will be understood that the oxidizing agent and conditions used are such as to convert the secondary hydroxyl group to the carbonyl group without further oxidizing the hydrocarbon.

This secondary hydroxy-to-carbonyl reaction is preferably carried out in the presence of a chromium trioxide catalyst because of its relative mildness and specificity.

The reaction is carried out under acidic conditions. Thus, inorganic acids such as sulfuric acid and the like or organic acids such as lower aliphatic acids like acetic acid can be used to provide the acidic reaction milieu. There is also preferably a reaction vehicle such as an aqueous vehicle present to permit moderation and control of the reaction and to facilitate contact of the oxidizing agent with the secondary alcohol.

A temperature is maintained sufficient to provide a satisfactory rate of oxidation while avoiding further oxidation beyond the alcohol. It has been found that the reaction can be carried out at temperatures of from -5° C. to the reflux temperature of the aqueous reaction system. It is generally preferred to carry out the oxidation at temperatures on the order of 20°-30° C. since this provides an acceptable reaction rate and minimizes side reactions.

The reaction can be carried out under atmospheric or sub- or superatmospheric pressures. However, because of the moderate temperature requirement of the reaction, atmospheric pressure is suitably used.

The novel ketones of this invention are conveniently prepared from beta-patchoulene having the structure

(1,4,9,9-tetramethyl- $\Delta^{3a,8a}$ -octahydro-4,7-methanoazulene)

or delta-patchoulene having the structure

(1,4,9,9-tetramethyl- $\Delta^{3a,8a}$ -octahydro-4,7-methanoazulene)

10 by converting these materials to the saturated alcohols and then oxidizing the alcohol to the ketones as disclosed above. One method of obtaining the alcohol is by a direct oxidation of the patchoulene to provide the unsaturated ketones, as described in the copending application of Braja D. Mookherjee, entitled "Novel Process and Product," Ser. No. 735,545 filed June 10, 1968, now U.S. Pat. 3,679,750 herewith, and then hydrogenating the unsaturated ketones to produce the saturated alcohols. A novel method for preparation of the alcohols according to the present invention comprises treatment of the patchoulene with a diborane source to form a boron addition compound and then oxidizing and hydrolyzing the rearranged addition compounds to provide the secondary alcohols.

15 The novel ketones of the present invention can also be produced from "patchouli alcohol," stated by Buchi et al., 86 J.A.C.S. 4438 et seq. (1964) to have the structure

30

This alcohol is dehydrated under acid conditions to delta patchoulene. beta-Patchoulene is readily prepared according to the method of Bates and Slagel, 84 J.A.C.S. 1307 (1962).

35 The preparation of the monounsaturated methanoazulenone has been described in the aforesaid copending application Ser. No. 735,545. The monounsaturated methanoazulenone produced by the process can be represented by the following structure:

50

wherein one of the dashed lines is a double bond and the other two dashed lines are single bonds, and one of R₂ and R₃ is oxygen and the other represents two hydrogen atoms.

55 The double bond of the methanoazulenone is hydrogenated and the keto group is simultaneously converted to a secondary alcohol group. The hydrogenation to obtain the secondary alcohol can be carried out with gaseous hydrogen in the presence of a hydrogenation catalyst such as Raney nickel, palladium on carbon, and the like. The reduction can also be performed using an alkali-metal 60 reduction process which utilizes sodium or other alkali-metal amide. It will be understood that the alkali-metal reduction can also be carried out by the use of an ammonium hydroxide system containing an alkali-metal such as sodium and a lower alkanol such as ethanol and 65 the like.

70 The hydrogenation of the monounsaturated methanoazulenone is carried out at a temperature sufficient to afford a reasonable reaction rate. For the alkali-metal reduction, substantial molar excesses of alcohol, 75 alkali-metal and ammonium hydroxide are used, based

on the quantity of methanoazulenone. Thus, ten or more moles of ammonium hydroxide and two to four moles of alkali-metal are used. It will be understood that sodium amide in alcohol can also be used in the same relative proportions as set forth above. The amide reduction process is preferably carried out at temperatures ranging from 0° to about 30° C.

According to a novel process, the perhydro secondary alcohol can also be prepared directly from beta-patchoulene, described above, by treatment with a diborane source to form the boron addition compound and oxidation and hydrolysis to form the aforesaid rearranged secondary alcohol having the formula

wherein R₄, R₅, and R₆ are stated above. The secondary alcohol so produced is then oxidized as disclosed above to provide the saturated ketone.

The beta-patchoulene utilized as the starting material is readily obtained by cyclizing bulnesol having the formula

in an acidic reaction medium to form a methano bridge. Bulnesol is conveniently obtained from guaiacwood oil. The cyclization is carried out by treating the bulnesol or bulnesol fraction of guaiacwood oil with p-toluenesulfonic acid and formic acid in a vehicle such as toluene. The mixture is heated at reflux until evolution of water ceases. The reaction mixture is then neutralized with alkali such as an alkali-metal hydroxide and distilled to obtain the beta-patchoulene.

beta-Patchoulene is treated with a diborane source such as diborane itself, an alkali-metal boro-hydride-aluminum chloride mixture, an alkali-metal boro-hydride-boron trifluoride mixture, and the like. The alkali metal borohydride sources of diborane which can be used include lithium borohydride-aluminum chloride, sodium borohydride-boron trifluoride, and the like. The reaction is desirably carried out in an inert vehicle in which diborane is soluble to facilitate control of the reactants, lower the reaction pressure, and permit moderation and control of the reaction. It will be understood by those skilled in the art that the formation of the boron adduct is to be carried out in a substantially water-free environment. Suitable reaction vehicles for use in the hydroboration reaction include high-boiling ethers such as tetrahydrofuran, dimethoxyethane, diglyme, and the like.

As noted above, the diborane can be supplied to the reaction either directly in the gaseous form or as a diborane-producing mixture such as alkali-metal boro-hydride-boron trifluoride. A preferred mixture is sodium borohydride-boron trifluoride.

In carrying out the reaction, it has been found that the proportions of beta-patchoulene and diborane can be varied over a range. Thus, equivalent quantities of patchoulene and diborane can be used in carrying out the process. It will be understood that, when a complex furnishing diborane to the reaction is used, the quantity

of the complex which can be used is that required to provide the desired proportion of diborane in the reaction. Generally, it is preferred that an excess of the diborane be present in the reaction mixture to assure complete reaction of the patchoulene and isomerization of the initially formed tertiary adduct. The formation of the boron adduct from patchoulene is preferably carried out at temperatures of 65° C. to 100° C.

After the boron adduct has been prepared, it is oxidized and hydrolyzed to the perhydro secondary alcohol shown above. Those skilled in the art will appreciate from the present description that the oxidation and hydrolysis can be carried out sequentially or substantially simultaneously in a single reaction mixture. The oxidation of the boron adduct is carried out through the use of a relatively strong oxidizing agent. Suitable oxidizing agents for this step of the process include hydrogen peroxide and acid-dichromate media. Hydrogen peroxide strengths of from about 20 to about 60% are preferred. When an acid-dichromate medium is utilized, the acid is preferably a strong inorganic acid such as sulfuric and the chromate is provided by chromic trioxide or an alkali-metal dichromate such as potassium dichromate and the like. All percentages, parts, proportions and ratios herein are by weight, unless otherwise indicated.

The oxidation reaction is carried out at temperatures which afford a good reaction rate while minimizing undesirable side reactions. Thus, when hydrogen peroxide is used as an oxidizing agent to form the perhydro secondary alcohol, temperatures on the order of from 20° to 40° C. are used. When an acid-dichromate medium is used, the temperatures can range from 15° C. to 40° C. The time for carrying out the reaction can vary, and it has been found that good yields are obtained in 1/2 to 2 hours.

The hydrolysis to provide secondary alcohols is preferably carried out with a strong base. Examples of preferred strong bases are the alkali-metal hydroxides such as sodium hydroxide, potassium hydroxide, and the like. When hydrogen peroxide is the oxidizing agent, the base can be added to the boron adduct before the treatment with peroxide.

For convenience, the perhydro alcohol obtained when R₄ is hydroxyl will be referred to as "3-ol"; when R₅ is hydroxyl, "2-ol"; and when R₆ is hydroxyl, "8-ol." The proportion of each of these isomers obtained by hydroboration and oxidation-hydrolysis of beta-patchoulene varies according to the concentration of the reactants, the temperature of the hydroboration reaction, and to a lesser extent the time of reaction and whether the reaction is performed by adding oxidation agents directly to the hydroboration reaction mixture or whether a separation is first performed. It has been found in carrying out the process of this invention that the 2-ol is generally the major product, the 3-ol is obtained in lesser amounts, and the 8-ol is obtained in relatively small quantities. It will be appreciated that the oxidation of the secondary alcohol to provide the perhydro ketone will generally provide the keto-isomer corresponding to the secondary alcohol isomer. For instance, oxidation of the 2-ol provides the corresponding 2-one (II).

Depending upon the particular isomer or isomer mixture of ketones prepared according to this invention, the intermediate products, e.g., the boron adduct, the monounsaturated methanoazulenone, the perhydro secondary alcohol, can be purified and/or isolated as desired. Alternatively, purification and/or isolation can be carried out on the final perhydro ketone product. At least the final perhydro ketone is desirably purified to remove unreacted materials, by-products, color bodies, foreign odor bodies, and the like. The purification and/or isolation of the intermediates and the final ketonic products can be carried out by conventional techniques. Thus, the intermediate and final products can be purified, separated, and/or isolated by distillation, extraction, preparative chromatographic techniques, and the like.

The ketones obtained according to this invention have an amber, precious wood fragrance note. This fragrance note is quite intense, and relatively small quantities of the ketones according to this invention confer such a fragrance note on perfumed articles, perfume compositions and other olfactory agents. Moreover, the novel ketones herein disclosed maintain substantially the same fragrance note over a period of time on a blotter, so that formulation of olfactory agents is facilitated and simplified.

The following examples are given to illustrate embodiments of the invention as it is presently preferred to practice it. It will be understood that these examples are illustrative and the invention is not to be considered as restricted thereto except as indicated in the appended claims.

EXAMPLE I

Hydroboration of beta-patchoulene followed by oxidative hydrolysis to produce secondary alcohol mixture

A 20-liter reaction vessel is charged with 2500 ml. of tetrahydrofuran and 640 g. of sodium borohydride, and 2800 g. of boron trifluoride etherate is added dropwise to the mixture. Eighteen hundred and fifty grams of 1,4,9,9-tetramethyl- $\Delta^{3a,8a}$ -octahydro-4,7-methanoazulene (beta-patchoulene) is added to the reaction mass, and the mass is refluxed at atmospheric pressure for eight hours.

After cooling to 25° C., 300 ml. of water is added over a 30-minute period while the mass is maintained at 25° C. Six and three tenths grams of 3.0 M aqueous sodium hydroxide is then added with stirring during 45 minutes. Fifteen hundred ml. of a 50% solution of H_2O_2 is added at 25° C. over 75 minutes. After the addition is complete, the organic layer is separated, the aqueous phase is extracted twice with equal volumes of diethyl ether, and the ether extracts and the organic layer are combined, washed twice with equal volumes of 5% sodium chloride solutions, dried over anhydrous magnesium sulfate, filtered and concentrated on a flash evaporator. The yield of crude secondary alcohol mixture, containing secondary alcohols of the structure

wherein R₄, R₅, and R₆ are defined as above, is 2364 g. Gas-liquid phase chromatography (GLC) (8' $\times$ 1/4'—20% Carbowax 20M polyethylene glycol coated on "Anakron ABS" silanized acid-washed calcined diatomaceous earth made by Analab, Inc., Hamden, Conn. column; flow rate, 100 ml./min.; chart speed, 15"/hr.) indicates 82.2% of the 2-ol; 12.7% 3-ol; and 5.1% 8-ol.

EXAMPLE II

Oxidation of the secondary alcohol to the ketone

A 10-liter reaction vessel is charged with 888 g. of chromium trioxide, 3.8 liters of glacial acetic acid and 1600 ml. of water. A solution of 2254 g. of the alcohol mixture prepared in Example I in 2.2 liters of acetic acid is added dropwise to the mixture, while the temperature is kept at 25–30° C. The mixture is stirred until the exotherm ceases.

A solution of 250 g. of chromium trioxide in 600 ml. of glacial acetic acid and 100 ml. of water is then added to the reaction mass. The mass is maintained at 25–30° C. with stirring for 12 hours. At this point the reaction is 95% complete as indicated by GLC, and the acetic acid

5
10

is distilled off and the resulting crude oil washed twice with equal volumes of 5% sodium chloride-5% NaHCO₃ solution, dried over anhydrous magnesium sulfate, and filtered. The filtered material is rushed over (flash distilled) to yield 1338 g. of a crude mixture. This crude mixture is then distilled at 103°–144° C. at 0.8 mm. Hg pressure.

GLC (conditions set forth above) shows three peaks which are identified as three ketones having the generic structure:

15

wherein R₁, R₂, and R₃ are as defined above, the ratio of II:I:III being 70:21:5. The structures are confirmed by nuclear magnetic resonance (NMR) and infrared (IR) analyses. The mixture is separated and isolated (via GLC-conditions set forth above). Each of the three isomers possesses strong amber and patchouli fragrance notes, with additional camphoraceous notes. IR analysis of the three mixtures yields the following data:

30	Centimeters $^{-1}$		
	II	I	III
5-membered ring carbonyl.....	1,735	1,730	.....
Methylene alpha to carbonyl.....	1,412	1,410	1,410
gem-Dimethyl.....	1,365, 1,388	1,363, 1,388	1,364, 1,387
Methyl.....	1,375	1,375	1,375
6-membered ring carbonyl.....	.....	.....	1,735

35

EXAMPLE III

Hydroboration of beta-patchoulene followed by oxidation in situ

A 5-liter reaction vessel is charged with 1000 ml. of tetrahydrofuran, 80 g. of sodium borohydride, and 250 g. beta-patchoulene, and 183 g. of boron tetrafluoride-diethyl etherate is added (this being one-half of the amount required to convert all the sodium borohydride to diborane). The reaction mass is refluxed at atmospheric pressure for four hours and an additional 30 g. of boron trifluoride-diethyl etherate is then added to the mass. The mixture is refluxed again for a period of four hours.

40
45
50
55

The resulting mixture containing boron addition compounds is subjected to oxidative hydrolysis and final oxidation to the desired ketone in the same reaction vessel as follows: A mixture of

1000 g. 93% sulfuric acid
1000 g. water
150 g. sodium dichromate

60
65
70

is then added to the reaction mass with stirring, while the mass is maintained at 25° C. Stirring at 25° C. is continued GLC (using the parameters set forth in Example II) shows the reaction to be complete.

The phases are separated and the aqueous phase is extracted twice with equal volumes of diethyl ether. The ether extracts and organic layer are combined and washed three times with equal volumes of saturated sodium chloride solution, dried over anhydrous magnesium sulfate and treated in a flash evaporator to remove the diethyl ether. The crude ketone is then rushed over under good vacuum, and subsequently distilled at 103–144° C. at 0.8 mm. Hg pressure.

75
80
85
90
95

GLC (conditions set forth in Example II) indicates three ketones. The structures are confirmed by IR and NMR analysis to be the 2-one, 3-one, and 8-one. The ratio of II:I:III according to the GLC analysis is 30:24:15. The mixture produced has a strong amber,

patchouli, camphoraceous odor with an additional fine woody "cigar box" fragrance note. The 2-one and 3-one when separated by GLC have the same fragrance notes as those compounds obtained in Example II. IR analysis of the mixtures yields data identical to those obtained for the mixtures of Example II.

EXAMPLE IV

Perhydro ketones from patchouli alcohol

Three and seven-tenths grams of patchouli alcohol is dissolved in 3.5 ml. of distilled hexane, and 1.0 g. of cation exchange resin [Amberlite IRC 120(H)CP, a chemically pure sulfonated styrene-8% divinyl benzene copolymer having an exchange capacity of 1.7 meq./ml. (wet), manufactured by Rohm & Haas Co. of Philadelphia, Pa.] is added to the solution. The mixture is refluxed for five hours at atmospheric pressure. The ion exchange resin is then removed from the reaction mass by filtration and the mass is separated into three components using GLC (procedure of Example II): beta-patchoulene, delta-patchoulene, and the patchouli alcohol starting material.

Into a 100 ml. three-necked flask equipped with a condenser, nitrogen feed means, pressure-equilibrated dropping funnel, and magnetic stirring bar are placed the following materials:

123 mg. delta-patchoulene
trace zinc chloride
5 ml. anhydrous diethyl ether
1.0 g. sodium borohydride

The reaction mass is cooled to -5° C. and, maintaining this temperature, the mass is stirred for one hour. Boron trifluoride-etherate, 10 ml., diluted with 10 ml. of diethyl ether is added to the reaction mass over a period of 1½ hours, still maintaining the mass at -5° C. After stirring for one hour at -5° C., 2 ml. of water is added to destroy any remaining unreacted hydride. To the boron adduct mixture, 5 ml. of 3 M aqueous sodium hydroxide solution is added. Immediately thereafter, 7 ml. of a 30% H₂O₂ solution is added to the reaction mass during one hour while maintaining the temperature at -5° C. The reaction mass is then stirred at -5° C. for an additional two hours.

The organic phase is separated, and the aqueous phase is successively extracted with three 10 ml. volumes of diethyl ether. The ether extract is combined with the organic phase and the combination is then washed successively with three 10 ml. volumes of water, dried over anhydrous sodium sulfate, and stripped of diethyl ether. The crude material chromatographed over silicic acid (5% deactivated, 3 g.) is found to be the perhydro secondary alcohol.

To 40 mg. of this secondary alcohol dissolved in 2 ml. glacial acetic acid is added 50 mg. of CrO₃, dissolved in 1.5 ml. glacial acetic acid. The mixture is maintained at 0° C., for one hour, diluted with 10 ml. of water, and extracted with two successive 10 ml. portions of diethyl ether. The combined ether extracts are then washed with three 5 ml. portions of 2 N Na₂CO₃ and three 5 ml. portions of water. The washed ether extracts are dried over anhydrous sodium sulfate, and the solvent is removed to furnish crude ketone which is purified using the GLC procedure of Example II.

The purified ketone mixture has an amber, patchouli, camphoraceous odor. IR analysis of the mixture of ketones shows a 5-membered ring moiety at 1735 cm.⁻¹. Mass spectral analysis shows a molecular ion at m/e of 220. The mass spectra, IR and NMR analyses confirm I and II.

EXAMPLE V

Perhydro ketone from direct oxidation of beta-patchoulene

(A) Oxidizing agent preparation: Into a 3-liter reaction flask equipped with a reflux condenser, Y-tube, stirrer

and nitrogen purge means is placed 1.2 liters of t-butyl alcohol. With nitrogen purging, 400 g. of anhydrous chromium trioxide is added over one hour. The mass is then dissolved in 2 liters of carbon tetrachloride, washed with three 500 cc. portions of water and dried over anhydrous sodium sulfate.

(B) Direct oxidation: Into a 12-liter reaction flask equipped with a reflux condenser, stirrer, Y-tube, thermometer and addition funnel, are introduced the following materials:

200 g. beta-patchoulene
2 liters carbon tetrachloride
160 cc. acetic anhydride
600 cc. acetic acid

15 The mass is stirred and heated to 50° C.

A solution consisting of 3½ liters of the chromium trioxide-t-butyl alcohol complex prepared as in (A) 160 cc. acetic anhydride, and 600 cc. of acetic acid is prepared. This solution is added dropwise to the beta-patchoulene solution over a 2½ hour period, while the reaction mass is maintained at 50° C. The reaction mass is stirred for a period of 20 hours at 50° C. and washed with a solution of 1500 g. oxalic acid dissolved in 12 liters of water.

25 The organic layer is separated from the aqueous phase and washed with two 500 cc. portions of water, neutralized with a saturated sodium carbonate solution, and washed twice again with two successive 500 cc. portions of water. The washed material is dried over anhydrous sodium sulfate and concentrated under vacuum.

The crude concentrated material is distilled at 113-148° C. at 1.8-0.8 mm. Hg pressure.

(C) Reduction: The distilled product, 2.5 g., produced by the foregoing direct oxidation is dissolved in 3 cc. of benzene and 3 cc. of aqueous saturated NH₄OH in a 50 cc. three-neck reaction flask equipped with a reflux condenser, thermometer, and magnetic stirring bar. The reaction mixture is cooled to 5° C. To the cooled mass, 0.8 g. of sodium particles are added over one hour. The temperature of the reaction mass is maintained between 10 and 15° C. After a one-hour period, 3 cc. of benzene and 5 cc. of aqueous saturated NH₄OH are added to the reaction flask. Then 0.8 g. of sodium particles are added over a ½ hour period. The reaction mass is then stirred for 2 hours at 25° C. and stored at 0° C. for a period of 13 hours. Two phases thereupon exist in the reaction mass: an organic phase and an aqueous phase.

35 The organic phase is washed with 5 cc. of a 3.7% solution of HCl and washed twice with 5 cc. portions of distilled water. The washed organic phase is dried over anhydrous sodium sulfate, and the benzene solvent is removed with nitrogen. IR analysis indicates that a substantial portion of the ketone is reduced to perhydro secondary alcohol.

(D) Oxidation: The secondary alcohol formed in the immediately preceding section is dissolved in 9 cc. of glacial acetic acid and cooled to 0° C. To this solution is added a solution consisting of 350 mg. chromium trioxide dissolved in 12 cc. of glacial acetic acid and 0.3 ml. of distilled water. The reaction mass is stirred and maintained at 0° C. during the addition. The mass is then stirred at 24-25° C. for a period of one hour.

65 The reaction mass so obtained is poured into 30 cc. of distilled water in a 250 cc. separatory funnel and extracted four times with 25 cc. portions of diethyl ether. The ether extracts are combined and washed with 10% Na₂CO₃ solution until basic. They are then washed with distilled water until neutral, dried over anhydrous sodium sulfate, and concentrated under vacuum. The resulting crude ketone mixture is distilled at 110-140° C. under 0.8 mm. pressure. IR, NMR and mass spectral analyses show the presence of I, II and III. The purified ketone mixture has an amber, patchouli, camphoraceous odor with a woody-cigar box note.

EXAMPLE VI

Perfume composition

A perfume composition is prepared with the following ingredients:

	Parts
Vetivert oil	40
Ketone mixture of Example II	60
Sandalwood oil	100
Rose geranium oil	200
Musk extract (3%)	25
Civet extract (3%)	25
Benzyl-iso-Eugenol	100
Coumarin	100
Heliotropin	50
Bois de Rose oil	200
Benzoin resin	100
	1000

The perfume composition exhibits an excellent woody fragrance. When the ketone mixture is omitted, the composition lacks the woody, amber fullness of the complete perfume composition of this example.

It will be understood from the present description that I, II and III produced according to the present invention can be used separately or in combination with each other to provide a good intense amber, woody fragrance note.

EXAMPLE VII

The Example II mixture is evaluated against the known material "patchoulione" by preparing a solution of each in diethyl phthalate and comparing blotter strips containing samples of the solutions. The "patchoulione" has a rooty earthy fragrance character, while the Example II material according to the present invention has an amber precious wood fragrance. The Example II material is much more intense, being at least twice as strong as "patchoulione," and maintains its strength and aroma pattern after several days' dryout on the blotter strips.

In the following examples, the soap base and soap chips used are unperfumed sodium-based toilet soaps made from tallow and coconut oil. The detergent powder is a material obtained from Lever Bros. Co. and sold under the trademark "Rinso." The liquid detergent is a product manufactured by Ultra Chemical Co., and is known as "P-87" liquid detergent.

EXAMPLE VIII

Preparation of soap composition

One hundred grams of soap chips are mixed with one gram of the perfume composition of Example VI until a substantially homogeneous composition is obtained. The perfumed soap composition manifests an excellent woody, amber, patchouli odor character.

EXAMPLE IX

Preparation of a detergent composition

A total of 100 grams of a detergent powder is mixed with 0.15 gram of the perfume composition of Example

12

VI until a substantially homogeneous composition is obtained. This composition has an excellent woody, amber odor.

EXAMPLE X

Preparation of a cosmetic powder composition

A cosmetic powder is prepared by mixing in a ball mill 100 grams of talcum powder with 0.25 gram of the mixture obtained from the process of Example III. A second cosmetic powder is similarly prepared except that the mixture of Example II is used. Both have excellent woody, amber, patchouli-like odors.

EXAMPLE XI

Perfumed liquid detergent

Concentrated liquid detergents with a woody, amber, patchouli-like odor are prepared containing 0.10%, 0.15% and 0.20% of the 3-one of this invention. They are prepared by adding and homogeneously mixing the appropriate quantity of the compound in the liquid detergent. The detergents all possess a woody amber fragrance, the intensity increasing with greater concentration of the ketone of this invention.

What is claimed is:

1. A perfume composition containing a perfume carrier or vehicle and a small amount of a ketone effective to impart a woody amber fragrance character to the composition, the ketone having the formula

wherein one of R₁, R₂ and R₃ is oxygen and each of the other two represents two hydrogen atoms, or mixture of said ketones.

2. The perfume composition of claim 1 additionally containing a surface-active agent.

3. The perfume composition of claim 1, additionally containing talcum.

UNITED STATES PATENT OFFICE
CERTIFICATE OF CORRECTION

Patent No. 3,748,284 Dated July 24, 1973
Inventor(s) James D. Grossman, Braja D. Mookherjee,
Robert S. De Simone, and Ernest T. Theimer

It is certified that error appears in the above-identified patent and that said Letters Patent are hereby corrected as shown below:

In the designation of the inventors:

"Crossman" should read --Grossman--

Col. 2, line 4, "anozulen" should read --anoazulen--

Col. 4, line 17, cancel "herewith".

Col. 5, lines 30-39, the correct formula should read:

Col. 6, line 4, "by" should read --be--.

Col. 6, line 62, correct the spelling of "according".

Col. 12, claim 2, line 1, correct the spelling of "claim".

Signed and sealed this 20th day of November 1973.

(SEAL)
